UNITED STATES PATENT OFFICE.

STILLMAN A. CLEMENS, OF CHICAGO, ILLINOIS.

IMPROVEMENT IN MACHINES FOR THRASHING FLAX.

Specification forming part of Letters Patent No. 59,360, dated November 6, 1866.

To all whom it may concern:

Be it known that I, STILLMAN A. CLEMENS, of Chicago, Cook county, Illinois, have invented a new and useful Machine for Removing Seed-Ends from Straight Flax-Straw, and Thrashing and Winnowing Flaxseed; and I do declare the following to be a full, clear, and exact description of the same, reference being had to the accompanying drawings, making part of this specification, in which—

Figure 1 is a vertical longitudinal section. Fig. 2 is a vertical cross-section, and Figs. 3 and 4 are side elevations.

Like letters refer to like parts in all the figures.

My said invention consists in mechanical devices combined in a machine, by which the seed-bolls and seed-ends of straight flax-straw are simultaneously removed from the flax-stalks, and the seed-bolls crushed and the flax-seed winnowed.

In the accompanying drawings, *a* is the frame of the machine; *b* is a toothed cylinder, made to revolve at high speed in the direction of its arrow.

c c' are a pair of pressure crushing-rollers set in their bearings so that their circumferences shall not quite touch each other, (to avoid crushing flaxseed passing between them,) and the roller *c'*, having narrow, shallow channels or grooves cut lengthwise in its surface to give adhesion to the material passing between the rollers.

Motion is given to *c* in the direction of the arrow by a band, *d*, passing over a grooved pulley, *e*, on the shaft of *b*, and over a grooved pulley, *e'*, on the shaft of *c*.

c and *c'* are geared together by the spur-wheels *f f'*, the latter of which is smaller than the former, giving greater surface-speed to *c'* than to *c*, for the purpose of producing a drawing and rolling action upon the seed-bolls passing between them, and thus aiding in opening them and freeing the seed as the bolls are crushed.

g g' are chute-sides for directing the material thrown from *b* down upon and between the crushing-rollers *c c'*.

h is a sieve-shoe, with a horizontal or inclined screen or sieve, *i*, and an inclined screen, *k*, (the latter finer than the former,) which is suspended loosely near one end by a rod, *l*,

passing through its sides, which is supported at its ends in the frame *a*. The other end of the sieve-shoe rests on a cross-piece of the frame *a*, and is secured to it loosely by the pin *m*.

A horizontally vibrating and shaking motion is given to one of the sieve-shoe ends by an arm, *n*, attached to it, which, by the spring *o*, is made to bear against a prism, *p*, formed on the end of the shaft of *c'*.

q is a fan-blower for winnowing the flaxseed attached to one end of the shaft of *b*. The air-blast formed by it is conducted down a trunk, *r*, and directed horizontally and lengthwise through the sieve-shoe *h*, passing both above and below the screen *i*.

s is a cover to the cylinder *b*, curved and set to clear the points of its teeth, and resting on and secured to the top of the sides of the machine.

The partitions *t t* are set vertically at right angles to the axis of *b*, and attached to the cover *s*, and resting on and secured to the cross-pieces of the frame. They pass over the upper half of the cylinder *b* and between its teeth, their lower edges clearing the surface of the cylinder, thus dividing the upper surface of the cylinder into three sections for the purpose of forming three separate places for feeding the flax to the machine, so that three workmen can feed to the same machine at one and the same time, one on one side and two on the other side. For this purpose, also, there is one open space, *u*, formed in the cover at one side of the machine, (shown in Fig. 3,) which is an opening to the middle section of the cylinder, formed by the partitions *t t*; and also there are two similar spaces, *u' u''*, formed in the cover on the other side of the machine, (shown in Fig. 4,) which are openings to the end sections formed by the partitions *t t*.

A breast, *v*, on which the flax rests while held to the action of the cylinder, is secured to the cover, and extends across and above the feed-space *u*; and breasts *v' v''*, for the same purpose as the breast *v*, and formed of the upper part of a cross-piece of the frame *a*, extend across and below the feed-spaces *u'* and *u''*, on the opposite side of the machine from *v*.

In operating the machine suitable motion is given to the cylinder *b* by motive power applied to its shaft, which, by the connections

before described, drives the crushing-rollers *c* and *c'*, the fan *q*, and shakes the sieve-shoe *h*.

Small bundles of straight flax are taken by their butt-ends in the hands of workmen, and the seed-ends of the bundles are thrust into the feed-spaces *u u' u''*, so that the teeth of the cylinder *b* shall penetrate the ends of the bundles sufficiently to reach the seed-bolls and the seed-ends and branches of the flax-stalks. The bundles of flax are held to the action of the cylinder-teeth only long enough for them to whip and beat off the seed-bolls and seed-ends, which are thrown down and directed by the chute-sides *g g'* upon and between the crushing-rollers *c c'*, which last draw the seed-ends and seed-bolls between them, crushing and opening the seed-bolls and freeing the flaxseed from them; and the material passing from the crushing-rollers falls upon the screen *i* of the sieve *h*, and the air-blast from the trunk *r* bears away, through the open rear end of the sieve, the hulls of the bolls and seed-ends and light refuse material, while the flaxseed, aided by the shaking and vibrating of the sieve-shoe, falls down through the holes in the screen *i*, and is received upon the finer screen *k*, and, by its shaking and vibrating motion and its inclination, the flaxseed moves down the inclined plane of the screen, and is winnowed by the air-blast from *r*, and is finally discharged from the lower end of the screens. The refuse seeds and heavy matter mixed with the flaxseed is separated from it by escaping down through the holes in the screen *k*, which are too small for the flaxseed to pass through.

Certain modifications of the devices described may be used, viz:

First. The cylinder *b* may be divided by partitions into more or less feed-sections than those represented, and the feed spaces or openings may be either on one or both sides of the machine, and the partitions may be dispensed with when the feed-spaces are only on one side of the machine.

Second. The crushing-rollers may both be channeled lengthwise, and both may be run at the same speed.

Third. But one crushing-roller, *c'*, may be used, and in the place of the other roller, *c*, a series of spring-plates, *w*, (represented in Fig. 2 by dotted lines,) may be used, which are fastened at one end to the support *x*, and which near their other ends bear against the surface of *c'* sufficiently to crush the seed-bolls as they are carried between the spring-plates and the

roller *c'*. In this case the roller *c'* may be driven by a cross-band passing over the pulley *c* on the shaft of *b* and over a pulley on the shaft of *c'*.

Fourth. The sieve-shoe *h* may be shaken either by lateral or longitudinal movement of the entire shoe, or by both movements combined, and it may be supported for these purposes in other ways than as shown.

Fifth. A concave, *y*, to cylinder *b* may be used, (represented in Fig. 2 by red-ink lines,) which is of the ordinary kind and attached to the frame of the machine underneath the cylinder, having below it the chute-sides *z z'*, for conducting the material falling between the concave bars *y' y'* to and between the rollers *c c'*. When the concave is used the part of the frame *v' v''* is removed to admit of the material carried over the concave being thrown out from the side of the machine.

By the described use of the concave the straw removed from the bundles of flax by the teeth of cylinder *b* will be separated from the seed and seed-bolls, and be thrown out at one side of the machine, while only the seed and seed-bolls and chaff will pass down through the concave bars and through the crushing-rollers, thus effecting better action of the crushing-rollers on the seed-bolls and of the winnowing apparatus in cleaning the seed.

Sixth. The winnowing attachment in the described combination, or both the winnowing attachment and the concave attachment, may be dispensed with and the remainder of the combination be used only for thrashing the flax.

I claim as new and of my invention—

1. The combination of the toothed cylinder *b* with crushing-rollers *c* and *c'*, or their equivalents, substantially as described, and for the purposes set forth.

2. The combination of cylinder *b* and crushing-rollers *c c'* with the vibrating sieve-shoe *h*, fan *q*, and air-trunk *r*, substantially as described, and for the purposes set forth.

3. The crushing device, consisting of roller *c'* and spring-plates *w*, substantially as described, and for the purposes set forth.

4. A concave, *y*, combined with the described machine, substantially as described, and for the purposes set forth.

STILLMAN A. CLEMENS.
